Inventor:

Heinrich Hillmann

UNITED STATES PATENT OFFICE

HERMANN HILLMANN, OF BERLIN-FRIEDRICHSHAGEN, GERMANY

FLOAT FOR HYDROPLANES, FLYING BOATS, AND THE LIKE

Application filed June 13, 1929, Serial No. 370,683, and in Germany June 19, 1928.

This invention relates to floats for hydroplanes, flying boats and the like and consists in a new construction of floats, said construction comprising essentially a main body and 5 a dovetail or fork-shaped stern associated with said main body. In addition to this, my invention comprises the specific arrangement of a main keel on the main body of the float and of additional keels on said dovetail or 10 fork-shaped stern as well as a specific conformation of the underside of said main body, said dovetail or fork-shaped stern and said keels.

Prominent objects of my invention are to 15 provide a construction of a float for hydroplanes, flying boats or the like which is possessed of greatest possible stability in lateral direction, said construction permitting easy manœuvring upon the water surface and convenient starting and landing with relatively 20 large useful loads as compared with the dead weight of the hydroplane or flying boat and the driving power required therefor.

Heretofore, these problems have been 25 solved only to an insufficient degree, the floats to be used in connection with hydroplanes in place of the carriages usually employed with aeroplanes having ordinarily been constructed essentially in accordance with the principles 30 of constructing high-speed water-vehicles. According to my invention far better results may be obtained, if floats are used which differ from the floats of ordinary construction in that they are constructed to the greatest possible extent in agreement with aerodynamic as well as in agreement with 35 hydrodynamic requirements. Floats constructed according to my invention may further be used with advantage as hulls or shells for flying boats. The floats constructed according to my invention may further successfully be used as hulls or shells of pure water-vehicles having extraordinarily high speed.

My invention will be more fully understood by reference to the accompanying drawing which shows forms of a float constructed according to my invention, the specific construction of the deck or upper part of 50 the float as well as the cellular construction

of the body of the float being omitted, as this is not of importance in connection with my invention. In the drawing, Fig. 1 is a side-view of a float constructed according to my invention, Fig. 2 a top-view on Fig. 1, Fig. 3 55 a top-view of a modified construction of float, Figs. 4 and 5 are cross-sections through several forms of the main body of floats, and Figs. 6 and 7 cross-sections through several forms of the dovetail or fork-shaped sterns 60 associated with the main body of the float. Like reference characters indicate like parts throughout the figures of the drawing.

The rear part or stern of the float *a* which forms part of my present invention is of special dovetail or fork-shaped construction, and consists of two parts *b*, *b*, the outer surfaces of said parts being parallel or approximately parallel to the longitudinal axis *d*—*d* of the float, or also slightly tapering towards 65 the rear as shown in Figs. 2 and 3. An important feature of my invention consists furthermore therein, that the outer surfaces of the fork, irrespective of their tapering or parallel form, are positioned within the 70 largest cross-section of the main body *a* of the float. The inner surfaces of the parts *b* may diverge towards the rear and towards below as indicated at *g* in Fig. 7. The said 75 inner surfaces, however, may also be of straight conformation and extend in vertical direction towards below, permitting to construct the bottom of said parts *b*, *b* either with a flat or V-shaped cross-sectional 80 conformation, the latter being indicated in Fig. 6. The centrally positioned main keel *f* of the float in this case may follow an upwardly inclined line of concave, convex or straight 85 form, said line extending as far as to the point *i* of the dovetail or fork-shaped parts *b*, *b*. The main keel may, for instance, merge 90 towards above into the fork of the stern along a curved line as indicated point *i* in Figs. 1, 2 and 3. The float furthermore may either be constructed so as to have either an 95 entirely smooth outer surface, without any steps therein, or one or more steps may be provided either at the main body *a* of the float or at the dovetail or fork *b*—*b* as indicated at *k* in Fig. 1, or one or more steps 100

may be provided on the main body *a* of the float or on both parts of the dovetail or fork *b*—*b*. During use on a water surface the float will be immersed into the water to a smaller or greater degree in accordance with the load temporarily imposed thereon, an average degree of immersion being indicated in Fig. 1 by the line *M*—*M* which represents the water surface. The principal properties of a float constructed according to my invention in the aforescribed manner are pointed out in the following:

During forward motion through the water, the float is being lifted to a considerable degree out of the water without causing an excessive immersion of the dovetail-shaped or forked stern and without causing water to flow over said stern. At the same time the water will move along the float in a fully smooth condition, with a minimum production of spray and a minimum production of waves at the front and rear part of the float. By so constructing the float one of the most important requirements will be fulfilled viz: that during forward motion the float will be automatically lifted out of the water. In addition to this, landing either on a smooth or moving water surface will be essentially facilitated by constructing the float according to my invention in the aforescribed manner. Owing to the similarity of the hydrodynamic and aerodynamic conditions, my present float likewise will offer a minimum resistance during being moved through the air, that is during the regular flight of a hydroplane.

In addition to the aforementioned characteristic features of the float, a great stability in lateral direction will result from the fact that the stern of the float is of dovetail or fork-shaped conformation.

In a modified construction, the float according to my invention may also be used as the hull or shell of a flying boat by providing upon the parts *b* which form the dovetail or fork-shaped stern of the float one or more fins in the form of a keel, as well as a stabilizing or balancing surface which may either pass in the form of a continuous surface along the body of the float or which may be composed of a plurality of surfaces with interstices therebetween. Furthermore, one or more vertical and horizontal rudders and one or more supporting surfaces may be provided on the body of the float. These supporting surfaces may be arranged in any suitable way, for instance, one above the other or staggered. Also the supporting surfaces may be made of any suitable height and width and arranged on the body of the float either in a right or acute angle thereto. Also, the motors which serve for driving the propellers—which may be thrust-propellers or draw-propellers or both—may be arranged above, below, besides or intermediate said

surfaces. The arrangement of such surfaces and the like is well known and has therefore not been incorporated in the drawing.

The float described in the foregoing may be further improved by giving a special conformation to the front part and to the rear part thereof. The front part of the float is preferably made in the form of a heavily bilged hollow frame, while the ribs or timbers of the main body of the float beginning at the front part are constructed in bind-water or plural V-form, the keels *n* and *f* being used for this purpose. This conformation of the bottom of the float may end at a step, if such step is provided; if no such step is used the said conformation may extend as far as to that point at which the bottom or main keel is carried towards above in the direction towards the stern. A float of this form is shown in section in Figs. 4 and 5.

In the construction shown in Fig. 2, the keel is sharp throughout its length so that the two parts of the dovetail or fork form an acute angle with each other. A still more favorable effect may be produced, if the keel extends in the form of a band or the like as shown in Fig. 3, towards the dovetail or forked end of the float, so that the inner surfaces of the dovetail or fork do no more form the apex of an angle but issue from a surface which is positioned transversely to the main axle *d*—*d* of the float. Either part of the dovetail or fork-shaped rear end of the float is provided with a special keel *n* commencing at the front part of the float and extending as far as to the end of either part *b* of the dovetail or fork-shaped rear end; these keels *n* furthermore form together with the keel *f* a double hollow frame or a hollow frame of plural V cross-section, while either part of the dovetail or fork-shaped end of the float is constructed in the form of a V-shaped frame as shown at *h* in Fig. 6.

While I have shown in the accompanying drawing and described in the foregoing specification some preferred forms of floats, boat hulls or the like, I desire of being understood that the specific disclosure is given for the purpose of exemplification only and that the scope of my invention is defined in the appended claims in which I have endeavored to distinguish it from the prior art, without, however, relinquishing or abandoning any part or feature thereof.

I claim:

1. A float for hydroplanes and flying boats, said float comprising a main body, a forked stern having interior surfaces diverging towards the rear and outer surfaces positioned essentially within the largest cross-section of said main body, and a keel on either part of said forked stern, said keel extending as far as to the front part of said main body.

2. A float for hydroplanes and flying

boats, said float comprising a main body, a forked stern having interior surfaces diverging towards the rear and outer surfaces positioned essentially within the largest cross-section of said main body, a keel on either part of said forked stern, said keel extending as far as to the front part of said main body, and a keel on said main body, said latter keel merging in a curved line towards above into the fork of said stern.

10 3. A float for hydroplanes and flying boats, said float comprising a main body, a forked stern having interior surfaces diverging towards the rear and outer surfaces positioned 15 essentially within the largest cross-section of said main body, a keel on either part of said forked stern, said keel extending as far as to the front part of said main body, and connected with the main keel and with the outer 20 body face by bilged hollow frames on the underside of said main body and of said stern.

4. A float for hydroplanes and flying boats, said float comprising a main body, a forked stern having interior surfaces diverging towards the rear and issuing from a surface positioned transversely to the main axis of the float, the outer surfaces of said forked stern being positioned essentially within the largest cross-section of said main body, and a 30 keel on either part of said forked stern, said keel extending as far as to the front part of said main body.

5. A float for hydroplanes and flying boats, 35 said float comprising a main body, a forked stern having interior surfaces diverging towards the rear and outer surfaces positioned essentially within the largest cross-section of said main body, a keel on either part of said forked stern, said keel extending as far as to the front part of said main body, and one or 40 more steps provided on the underside of said main body and said stern.

In testimony whereof I affix my signature.

45 HERMANN HILLMANN.
